HAIR CURLER

Harry H. Klein, New York, N. Y.

Application March 22, 1940, Serial No. 325,279

13 Claims. (Cl. 132—41)

This invention relates to a hair curler of the type wherein the hair is wound around a cylinder with provisions for gripping the hair preliminarily to winding and retaining the hair in wound state around the cylinder.

The principal object of the invention is to provide a conveniently utilizable, efficient, and improved hair curling device of the above type, with improved means for preliminary gripping of the hair, subsequent winding of the hair, concluding retention of the wound hair, and the general performance of the hair curler and resulting hair curling operation.

Other objects and advantages will hereinafter appear.

In the accompanying drawing,

Fig. 1 shows a general elevation of the hair curler of the invention.

Fig. 2 is a cross-sectional elevation, on an enlarged scale, of the hair curler shown in Fig. 1.

Fig. 3 is a fragmentary elevational view showing a detail of the invention.

Figs. 4, 5 are transverse cross-sectional end elevations of the hair curler, taken on the lines 4—4, 5—5 respectively.

Fig. 6 is an elevation, on a reduced scale, of a hair curler, showing a modification of the invention.

The hair curler 1 has a tubular cylinder 2, provided with ventilating perforations 3, for winding the hair therearound, and said cylinder consists of two fractional half-cylinders 4 having beak-like end portions 5 provided at their extremities with laterally projecting hollow lugs 6. One of the half-cylinders 4 is provided with a sectorial projection 7 that registers with a corresponding recess 8 formed in the other half cylinder, Figs. 3, 2, and said registering projections and recesses are located at the junctions of the beak-like portions 5 with the half-cylinders 4 proper, whereby pressure upon the terminals of the portions 5 causes the half-cylinders 4 to open or swing away from each other about said registering parts, which thus constitute a joint fulcrum or hinge 9 for the half-cylinders, Fig. 2. A cylinder 10 encases the portions 5, with their lugs 6 protruding through openings 11 formed in said cylinder, and a leaf spring 12 located between said portions has its terminals within and pressing against the lugs 6, as illustrated in Fig. 2, in which manner the half-cylinders 4 are normally maintained closed under tension. The cylinder 10 is provided with a marginal collar 13 and near thereto a bead 14, between which is located a circular framing 15 rotatably mounted about said cylinder and carrying a hair retaining arm 16, and between the framing 15 and collar 13 is situated a spring washer 17 that bears upon both of these parts laterally, in which manner the relative rotation of the retaining arm 16 with its

depending framing 15 about the cylinder 10 with its depending conjoint half-cylinders 4 is at all times maintained under frictional spring tension.

When utilizing the hair curler, the lugs 6 are pressed inwardly into cylinder 10, to open the half-cylinders as shown in Fig. 1, the end of the strand of hair is then placed between the half-cylinders 4, and then the lugs 6 are released, whereupon the half-cylinders 4 gain a grip upon the end of the hair by the tension of the spring 12. While the arm 16 is then held with one hand, the cylinder 10 is rotated with the other, and the winding of the hair is thereby continued around the cylinder 2, until the space between it and the arm is snugly filled. The device is then left upon the head in this condition for any requisite length of time, at the end of which it may be removed by pressing upon the lugs 6 to ease the grip upon the curl of hair and simultaneously sliding the cylinder 2 off and out from the formed curl. While the curler is maintained in operative condition upon the head when left thereon, any tendency of the cylinder 2 to rotate backwardly, relatively to the stationary arm 16 that retains the curl, is retarded by the frictional tension of said cylinder and arm produced by the action of spring washer 17 upon collar 13 of the knurled cylinder 10 and the framing 15 depending from the arm 16, whereby any accidental uncurling of the device from the formed curl is prevented.

According to the modification shown in Fig. 6, the entire hair curler is made in the manner shown and described in connection with Figs. 2, 3, but without possessing the hair retaining arm 16 of Fig. 1. This hair curler may be therefore utilized as set forth hereinabove, but it may be removed directly after the curl is formed, as may be required in a variety of hair curling conditions.

Variations may be resorted to within the scope of the invention, and portions of the improvements may be used without others.

Having thus described my invention, I claim:

1. A hair curler having the combination of a cylinder for winding the hair therearound consisting of a pair of semi-cylindrical elements pivoted to each other near their ends, spring means normally compelling said elements to combine to a cylindrical form for gripping the hair between them preliminarily to its being wound around said cylinder, and said cylinder carrying means for retaining the wound hair thereon.

2. A hair curler having the combination of a cylinder for winding the hair therearound consisting of a pair of semi-cylindrical elements pivoted to each other near their ends, spring means normally compelling said elements to combine to a cylindrical form for gripping the hair between them preliminarily to its being wound around said cylinder, said cylinder carrying means for retaining the wound hair thereon, a casing envelop-

ing said elements between said pivoting and said ends, and said enveloped portions of said elements having lateral projections protruding through said casing for therewith spreading apart said elements contrary to said spring tension.

3. A hair curler having the combination of a cylinder for winding the hair therearound consisting of a pair of semi-cylindrical elements pivoted to each other near their ends, spring means normally compelling said elements to combine to a cylindrical form for gripping the hair between them preliminarily to its being wound around said cylinder, said cylinder carrying means for retaining the wound hair thereon, a casing enveloping said elements between said pivoting and said ends, and said enveloped portions of said elements protruding through said casing for therewith spreading apart said elements contrary to said spring tension.

4. A hair curler having the combination of a cylinder for winding the hair therearound consisting of a pair of semi-cylindrical elements pivoted to each other near their ends for gripping the hair between them preliminarily to its being wound around said cylinder, a framing, means to retain the wound hair on said cylinder depending from said framing, and said cylinder being rotatable within said framing.

5. A hair curler having the combination of a cylinder for winding the hair therearound consisting of a pair of semi-cylindrical elements pivoted to each other near their ends for gripping the hair between them preliminarily to its being wound around said cylinder, a framing, means to retain the wound hair on said cylinder depending from said framing, said cylinder being rotatable within said framing, and means to frictionally arrest the relative rotation of said cylinder and framing.

6. A hair curler having the combination of a cylinder for winding the hair therearound consisting of a pair of semi-cylindrical elements pivoted to each other near their ends for gripping the hair between them preliminarily to its being wound around said cylinder, a framing, means to retain the wound hair on said cylinder depending from said framing, said cylinder being rotatable within said framing, and spring means to arrest the relative rotation of said cylinder and framing.

7. A hair curler having the combination of a cylinder for winding the hair therearound consisting of a pair of semi-cylindrical elements pivoted to each other near their ends, spring means normally compelling said elements to combine to a cylindrical form for gripping the hair between them preliminarily to its being wound around said cylinder, said cylinder carrying means for retaining the wound hair thereon, a casing enveloping said elements between said pivoting and said ends, said enveloped portions of said elements protruding through said casing for therewith spreading apart the said elements contrary to said spring tension, a framing, means to retain the wound hair on said cylinder depending from said framing, and said cylinder being rotatable within said framing.

8. A hair curler having the combination of a cylinder for winding the hair therearound con-

sisting of a pair of semi-cylindrical elements pivoted to each other near their ends, spring means normally compelling said elements to combine to a cylindrical form for gripping the hair between them preliminarily to its being wound around said cylinders, said cylinder carrying means for retaining the wound hair thereon, a casing enveloping said elements between said pivoting and said ends, said enveloped portions of said elements protruding through said casing for therewith spreading apart the said elements contrary to said spring tension, a framing, means to retain the wound hair on said cylinder depending from said framing, said cylinder being rotatable within said framing, and means to frictionally arrest the relative rotation of said cylinder and framing.

9. A hair curler having the combination of a cylinder for winding the hair therearound consisting of a pair of semi-cylindrical elements pivoted to each other near their ends, spring means normally compelling said elements to combine to a cylindrical form for gripping the hair between them preliminarily to its being wound around said cylinder, said cylinder carrying means for retaining the wound hair thereon, a casing enveloping said elements between said pivoting and said ends, said enveloped portions of said elements protruding through said casing for therewith spreading apart the said elements contrary to said spring tension, a framing, means to retain the wound hair on said cylinder depending from said framing, said cylinder being rotatable within said framing, and spring means to arrest the relative rotation of said cylinder and framing.

10. A hair curler having the combination of a cylinder for winding the hair therearound consisting of a pair of semi-cylindrical elements pivoted to each other near their ends, and spring means normally compelling said elements to combine to a cylindrical form for gripping the hair between them preliminarily to its being wound around said cylinder.

11. A hair curler having the combination of a cylinder for winding the hair therearound consisting of a pair of semi-cylindrical elements pivoted to each other near their ends for gripping the hair between them preliminarily to its being wound around said cylinder, a framing, and said cylinder being rotatable within said framing.

12. A hair curler having the combination of a cylinder for winding the hair therearound consisting of a pair of semi-cylindrical elements pivoted to each other near their ends for gripping the hair between them preliminarily to its being wound around said cylinder, a framing, said cylinder being rotatable within said framing, and means to frictionally arrest the relative rotation of said cylinder and framing.

13. A hair curler having the combination of a cylinder for winding the hair therearound consisting of a pair of semi-cylindrical elements pivoted to each other near their ends for gripping the hair between them preliminarily to its being wound around said cylinder, a framing, said cylinder being rotatable within said framing, and spring means to arrest the relative rotation of said cylinder and framing.

HARRY H. KLEIN.
